UNITED STATES PATENT OFFICE.

PAUL E. LUECKE, OF CHICAGO, ILLINOIS, ASSIGNOR OF ONE-HALF TO HORACE K. RYAN, OF CHICAGO, ILLINOIS.

INNER TUBE FOR VEHICLE-TIRES.

1,323,600.

Specification of Letters Patent.

Patented Dec. 2, 1919.

Application filed May 21, 1917. Serial No. 169,822.

To all whom it may concern:

Be it known that I, PAUL E. LUECKE, a citizen of the United States, residing at Chicago, in the county of Cook and State 5 of Illinois, have invented certain new and useful Improvements in Inner Tubes for Vehicle-Tires, of which the following is a description.

My invention relates to the resilient inner- 10 tube or air container for a pneumatic vehicle tire.

The object of my invention is to provide an inner-tube having a thickened wear resisting portion at its periphery of sufficient 15 strength to maintain a substantially smooth surface even where the interior of the casing is irregular or worn through, thus avoiding "blow outs" and reducing the risk of "puncture" to a minimum owing to the 20 thickness and resisting nature of the periphery of the tube.

To this end my invention consists in the novel construction, arrangement and combination of parts herein shown and described, 25 and more particularly pointed out in the claim.

In the accompanying drawings wherein like or similar reference characters indicate like or corresponding parts,

30 Figure 1 is a side elevation of a portion of my improved tube with parts removed and broken away to more clearly show the construction.

Fig. 2 is a section taken substantially on 35 line 2—2 of Fig. 1.

Figs. 3 and 4 are views similar to Figs. 1 and 2 respectively showing a slightly modified form of my improvement.

In the form shown in the drawings my 40 improved inner-tube comprises a tubular ring 1 of substantially the usual form with the inner bearing portion 2 formed of rubber or other suitable elastic material impervious to air in the usual manner and of substantially the usual form and construction. The outer or tread portion 3 is preferably formed of canvas or other non-elastic material treated with rubber or other suitable substance to render the same impervious to 45 air also. The inner and outer portions are preferably connected along their margins as at 4 and 5 by cement or vulcanizing to form a permanent connection capable of withstanding the various strains and deflections

incident to the various changes in shape of 55 the tube when in service.

In the form shown the non-elastic portion 3 of the tube is provided with an elastic covering or outer casing 6 preferably formed of rubber or other impervious material 60 similar to the inner portion 2 of the ring rigidly secured to the fabric 3 to further guard against the escape of gas or air from the tube and at the same time making it more convenient to secure the parts of the 65 tube together as well as providing a more reliable connection between them and also providing for making repairs in substantially the usual manner in case the tread of my improved tube should become punctured. 70 In the preferred form shown the non-elastic part 3 is comparatively thin at its margins and gradually increases in thickness toward its central portion, thus providing a wear resisting "tread" of sufficient strength 75 and rigidity to resist any inequality or weakness in the tread of the outer casing which ordinarily would result in a rupture or "blow out" of both the tube and casing.

In the form shown in Figs. 3 and 4 the 80 several parts are constructed substantially as shown in Figs. 1 and 2 except that the non-elastic portion 3 is provided with an inner lining 7 formed of elastic impervious material as well as the outer covering 6 thus 85 completely inclosing the non-elastic portion 3 in an impervious substance preferably of the same general character as the elastic inner portion 2 of the tube, the invention being to provide a tread which is secure 90 against the weakness usually resulting in ruptures or "blow outs" as well as providing against ordinary punctures and while the coverings 6 and 7 are described as being formed of material similar to that forming 95 the part 2 elasticity is not essential so long as it is impervious to air or gas and can be securely attached at its margins to the part 2 to assist in forming a permanent connection between the parts 2 and 3. 100

Also while in the foregoing I have described my improved tube as formed of two parts connected at their margins and contemplate the construction of my improvement by this method where it is desired to 105 reconstruct tubes of the usual form now in service, it is obvious that my improvement may be provided in any desired manner to

secure a non-elastic periphery for the tube by securing a non-elastic reinforcement or lining within the tube.

Having thus described my improvement it is obvious that various immaterial modifications may be made in my device without departing from the spirit of my invention, hence I do not wish to be understood as limiting myself to the exact form or construction shown.

What I claim as new and desire to secure by Letters Patent is:

A device of the class described comprising a tubular ring composed of two partly tubular parts constituting respectively inner and outer walls thereof, the part forming the inner wall of the tubular ring being

constructed of impervious elastic material of substantially uniform thickness throughout, and the part forming the outer wall of the tubular ring comprising a plurality of sheets of inelastic material and a layer of impervious elastic material permanently connected together, said sheets of inelastic material being of graduated widths and arranged to afford a reinforce increasing in thickness toward the central portion thereof. 20 25

In testimony whereof, I have hereunto signed my name in the presence of two subscribing witnesses.

PAUL E. LUECKE.
